US00D831040S

(12) **United States Design Patent** (10) Patent No.: **US D831,040 S**
(45) Date of Patent: **** Oct. 16, 2018**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Mani Amini**, San Jose, CA (US); **Samuel Howard Bebbington**, San Francisco, CA (US); **Gary Butcher**, San Jose, CA (US); **Elizabeth Caroline Cranfill**, San Francisco, CA (US); **Alan C. Dye**, San Francisco, CA (US); **Stephen O. Lemay**, San Francisco, CA (US); **Daamun Mohseni**, San Jose, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/628,073**

(22) Filed: **Dec. 1, 2017**

Related U.S. Application Data

(63) Continuation of application No. 29/567,730, filed on Jun. 11, 2016, now Pat. No. Des. 804,502.

CLAIM

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.
